UNITED STATES PATENT OFFICE.

JOHN SCHNEIDERMAN, OF GEORGE, IOWA.

FIRE-ALARM ATTACHMENT.

1,425,797.

Specification of Letters Patent. Patented Aug. 15, 1922.

Application filed May 5, 1919. Serial No. 294,816.

To all whom it may concern:

Be it known that I, JOHN SCHNEIDERMAN, a citizen of the United States, residing at George, in the county of Lyon and State of 5 Iowa, have invented certain new and useful Improvements in Fire-Alarm Attachments, of which the following is a specification.

This invention relates to attachments for fire alarms and has for its principal object 10 the production of a structure which will catch the hand of the person "turning in" such an alarm, thus holding the person until proper authorities arrive who can release the hand of such person, whereby a 15 person who fraudulently turns in the false alarm will be easily trapped.

Another object of this invention is an attachment for fire alarm boxes, wherein a retaining plate is releasably held in a set 20 position to catch a hand which turns in an alarm, since the turning in of the alarm will manually operate the trip mechanism, thus releasing the plate and allowing the same to move to a position to engage the 25 hand of the operator, while means are provided for holding the plate against return from such a released position.

One practical form of construction and 30 assembly of the present invention will be hereinafter described and is illustrated in the drawing, in which—

Figure 1 is a front elevation of the fire alarm box showing the casing of the attachment mounted thereon.

35 Figure 2 is a side elevation of the device.

Figure 3 is a vertical section through the casing and portions of the invention thereof illustrating several portions of the trap.

In the preferred embodiment of the present invention, about to be described, 5 indicates in general the ordinary fire alarm box having the usual closure 6. A box housing 7 has the usual key 8 extending thereinto, whereby when the key is turned 40 the closure 6 may be released in order to allow the fire alarm to be turned in, although the key 8 may be used in combination with such a device as when it is turned an alarm will be turned in. As above suggested, it is 45 the object of this invention to reduce the tendency of parties turning in false alarms, since the structure will catch the party turning in the alarm and retain the party until proper authorities arrive who can release 50 such a person.

The trap casing comprises a wall 9 which

is fixed upon the closure 6 of the box 5 in any suitable manner. The side walls 10 are provided with a front wall 11, while the bottom 12 is provided for the casing. 60

The cover 13 is hingedly mounted as indicated at 14 upon one of the side walls and has flanges 15 thereon for forming a weather tight closure at the upper portion of the casing. A suitable locking arrangement as 65 indicated in general at 16 is provided for holding the cover 13 in a closed position.

The front wall 11 is provided with an opening therein surrounded by the cup 17. This cup 17 extends into the casing in direct alignment with the key 8, whereby a person may insert his hand through the cup 17 and engage the key and turn the same when an alarm is to be turned in, or when the closure 6 is to be opened for permitting 70 of the turning in of such an alarm.

The retaining plate 18 extends transversely across the casing as shown in dotted lines in Figure 1 and the pivot pin 19 passes through the plate 18 adjacent one end thereof and the pin 19 is carried by the side walls 10, thus pivotally supporting the plate 18. A strip of felt 20 or other suitable material is fixed upon the opposite lower edge of the plate 18, whereby when the plate moves into 80 a position to catch the hand inserted in the casing it will not injure the hand.

The supporting arm 21 is fixed in any desired manner on the plate 18 and has a weight 22 thereon, thus urging the plate 90 into a firm engagement with the hand of the wrist inserted into the casing.

In order to hold the plate 18 in a set position a locking structure is provided. An ear 23 is carried by the cover 13 and the 95 latch lever 24 is pivotally mounted intermediate its ends by the pin 25 upon the ear 23. This latch lever 24 has a claw 26 engaging the lug 27 extending from the end of the arm 21 upon which the weight 22 100 is carried. The spring 28 may be interposed between one end of the lever 24 and the cover 13 to firmly hold the claw in engagement with the section 27. The opposite end of the latch lever supports a connecting link 105 30, the opposite end of this link 30 being connected to the shank 31 extending from the key 8.

A curved rack bar 32 extends from the retaining plate 18 and has a rack 33 thereon. 110 This rack bar extends into the rack sleeve 34 carried by the cover 13. The rack sleeve

34 is arcuate to conform to the curvature of the rack bar 32. The pawl 35 is fixed upon the outer portion of the rack sleeve 34 and has a bent end 36 lying in the path of movement of the rack 33 on the bar 32.

When this device is in use, it will be set to assume the position shown in Figure 3. However, when a person inserts his hand and wrist through the cuff 17 to grip and turn the key 8, to open the closure 6 when an alarm is to be turned in, or to direct the turning in of the alarm by turning the key 8, the shank 31 will be swung to one side thus drawing upon the link 30. As the link 30 is moved downwardly it will swing the lever 24 upon its pivot, thus moving the claw 26 from engagement with the projection 27, whereby due to the force of gravity the plate 18, as well as the arm 21 and weight 22 will move downwardly to the position indicated in dotted lines in Figure 3, thus catching the hand of the person as shown in the figure just referred to. It will be impossible for such person to move the plate back from such a "sprung" position, since the rack bar 32 will have been retracted for a considerable distance from the rack sleeve 34 and the pawl 35 will prevent such rearward movement. Thus the party turning in the alarm will be caught and he cannot release himself, although the felt 20 will prevent injury to such person's hand. When the proper authorities have arrived, they can release the locking arrangement shown at 16 and the cover may be lifted to cause the plate 18 to disengage the person's hand extending through the cuff 17, whereby such person will be freed.

At this time the plate 18 may be swung upwardly, by the raising of the pawl 35 to permit the rack bar to move into the sleeve. The claw 26 may then be latched in engagement with the projection 27, thus holding the plate in a set condition.

It will thus be seen that an attachment is provided for the closure of a fire alarm, which is in a set condition to catch a person's hand inserted to turn in the alarm. However, it will be noted that the retaining plate will not injure the hand, but is provided with an efficient means for preventing unauthorized disengagement from the hand, although the authorized party may easily remove the plate and again set the same in position for future use.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

The combination of a casing having an opening therein an alarm mechanism projecting in the casing, a retaining plate pivoted at its upper edge above the opening in said casing and adapted to swing vertically, an arm extending laterally from said retaining plate, a weight carried by the end of the arm, a latch lever pivotally mounted within the casing and engaging the weight for holding the retaining plate in a raised position, a connection between said lever and said alarm mechanism whereby the lever is operated when the alarm mechanism is actuated, and means for retaining the retaining plate in a lowered closed position.

In testimony whereof I affix my signature in presence of two witnesses.

JOHN SCHNEIDERMAN.
